UNITED STATES PATENT OFFICE.

ANDREW IZOLD, OF CAMP MEADE, MARYLAND.

TOY MUSICAL INSTRUMENT.

Application filed August 1, 1922. Serial No. 579,024.

To all whom it may concern:

Be it known that I, ANDREW IZOLD, a citizen of the United States of America, residing at Camp Meade, in the county of Anne Arundel and State of Maryland, have invented certain new and useful Improvements in Toy Musical Instruments, of which the following is a specification.

This invention relates to certain new and useful improvements in wind musical instruments particularly servicable as a novelty and a toy for the amusement of children.

The primary object of the invention is to generally simplify and improve devices of this kind and to provide a novel toy which will effectively furnish amusement for the younger set.

Another object of the invention is to provide means for regulating the flow of wind or air from the inflatable air container to the sound producing diaphragm or reed of the instrument so that proper flow of air may be had to obtain sound devoid of shrillness and whereby the supply of air may be conserved for permitting a somewhat long playing of the device from one supply of air to the inflatable air container.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of a wind musical instrument constructed in accordance with the present invention and with the agitator shown inflated.

Figure 2 is an enlarged fragmentary view partly in side elevation and partly in section showing the upper portion of the inflatable air chamber and the manner of attaching the supply and outlet tubes thereto,

Figure 3 is an end elevational view of the inner end of the outlet tube showing the control valve for regulating the supply of air or wind through the reed or diaphragm,

Figure 4 is a fragmentary longitudinal sectional view of the inner end portion of the device shown in Fig. 3,

Figure 5 is a sectional view on line V—V of Fig. 4,

Figure 6 is a similar view on line VI—VI of Fig. 4, and

Figure 7 is a side elevational view of the device shown in Fig. 4.

Referring more in detail to the several views, the present device embodies an inflatable elastic air bag or container providing an air chamber and denoted by the numeral 5 formed with a reduced upper end portion as at 6 which is provided with openings diametrically opposite each other as at 7 and 8 and from which extend tubular nipples 9 and 10 respectively adapted for reception of and attachment to the supply tube 11 and outlet tube 12 respectively.

The mouth piece or supply tube 11 has its inner end fastened as at 13 in the nipple 9 and is provided at its inner end with a check valve 14 so arranged as to permit the free flow of air into the air bag 5 while preventing such air to blow outwardly through the mouth piece 11 in a well known manner. The outlet tube 12 is secured at its inner end as at 15 in the nipple 10 and may be flared in trumpet shape at its outer end as at 16 if found desirable for producing a desirable appearance.

Within the inner ends of the outlet tube 12 is a cup-shaped control valve 17 which is axially rotatable in the tube 12 within such limits as determined by the length of a circumferential elongated slots 18 provided in the outlet tube 12 and through which opposed pins 19 project, said pins being rigid with and projecting radially outwardly from the valve 17 as clearly shown in Figs. 4, 6 and 7. The inner end of the outlet tube 12 is preferably provided with an end wall 20 having slots or openings 21 therein adapted to cooperate with similar slots or openings 22 provided in the end wall of the valve 17. Obviously, by bringing the openings 21 and 22 in alinement, a full flow of air will be allowed to pass from the inflatable air bag 5 while a slight rotation of the valve 17 will more or less cut off this flow as desired. The pins 19 will engage the end walls of the slots 18 either when the valve is completely open or completely closed.

Outwardly of the valve 17, the outlet tube 12 has a centrally apertured plug 23 fastened therein which has a resilient strip of material 24 stretched across its central opening so as to act as a reed or diaphragm

for producing sound when the air flows from the air container 5. This sounding reed is of ordinary and well known construction and need not be further described.

- 5 The outlet tube 12 is provided with a regular series of openings 25 in the wall thereof adapted to be selectively closed or opened by the fingers whereby the different notes may be sounded in the usual manner 10 for permitting the rendition of simple music, and it is noted that the reed is located between the valve 17 and these openings 25.

In using the device the valve 17 is closed and the mouth piece 11 is placed in the 15 mouth whereupon the inflatable air bag 5 is inflated to the desired extent by blowing into the mouth piece. When it is desired to play the instrument the valve 17 is slightly rotated until the proper sound 20 is produced through the necessary amount of air escaping from the air container 5 and acting upon the reed 24. In this way the air supply is conserved as unnecessary additional or extra flow of air from the 25 container can be prevented whereby the production of objectionable shrill sound is eliminated, and then the different notes may be sounded through the proper closing and opening of the openings 25.

30 It is believed that the construction and operation as well as the advantages of the present invention will be readily understood and appreciated by those skilled in the art.

35 Minor changes may be made in the invention without departing from the spirit and scope thereof as claimed.

What is claimed as new is:

1. In a wind musical instrument of the 40 class described, the combination of an inflatable air container having opposed inlet and outlet openings, an inlet, mouth piece tube attached to the air container at the inlet opening, an outlet tube attached to the 45 container at the outlet opening, a check valve associated with the mouth piece to permit flow of air into the container while preventing escape of the air therefrom through the mouth piece, a sound producing reed 50 associated with the outlet tube, and means to control the supply of air from the container to said reed.

2. In a wind musical instrument of the 55 class described, the combination of an inflatable air container having opposed inlet and outlet openings, an inlet, mouth piece

tube attached to the air container at the inlet opening, an outlet tube attached to the container at the outlet opening, a check valve associated with the mouth piece to 60 permit flow of air into the container while preventing escape of the air therefrom through the mouth piece, a sound producing reed associated with the outlet tube, means to control the supply of air from the container to said reed, said air container being reduced in size at its upper portion, said upper portion having its opposite portions provided with the inlet and outlet openings in which the mouth piece and outlet tube 70 are secured.

3. In a wind musical instrument of the class described, the combination of an inflatable air container having opposed inlet and outlet openings, an inlet, mouth piece 75 tube attached to the air container at the inlet opening, an outlet tube attached to the container at the outlet opening, a check valve associated with the mouth piece to permit flow of air into the container while preventing escape of the air therefrom through the mouth piece, a sound producing reed associated with the outlet tube, means to control the supply of air from the container to said reed, said controlling means 80 comprising a valve associated with the outlet tube between the reed and said air container.

4. In a wind musical instrument of the class described, the combination of an inflatable air container having opposed inlet and outlet openings, an inlet, mouth piece tube attached to the air container at the inlet opening, an outlet tube attached to the 90 container at the outlet opening, a check valve associated with the mouth piece to permit flow of air into the container while preventing escape of the air therefrom through the mouth piece, a sound producing reed associated with the outlet tube, means to 95 control the supply of air from the container to said reed, said controlling means comprising a valve associated with the outlet tube between the reed and said air container, said outlet tube having a series of openings for 100 producing various notes through opening and closing of the same by the use of the fingers.

In testimony whereof I affix my signature.

ANDREW IZOLD.
